UNITED STATES PATENT OFFICE.

DAVID A. EBINGER, OF COLUMBUS, OHIO, ASSIGNOR TO THE D. A. EBINGER SANITARY MFG. CO., OF COLUMBUS, OHIO, A CORPORATION OF OHIO.

WATER CLOSET.

Application filed August 31, 1922. Serial No. 535,377.

To all whom it may concern:

Be it known that I, DAVID A. EBINGER, a citizen of the United States, residing at Columbus, in the county of Franklin and 5 State of Ohio, have invented certain new and useful Improvements in Water Closets, of which the following is a specification.

The present invention is directed to improvements in water closets, and more particularly to means for ventilating the same.

The primary object of the invention is to provide a device of this nature which can be easily attached to the bowl in a position to keep the same free from obnoxious odors 15 and gases.

A further object of the invention is to provide a ventilator for use in connection with a vitreous china bowl, the ventilator being formed from metal which is enameled 20 to correspond with the finish of the bowl, the ventilator being separately connected so as to reduce the molding cost of the bowl, and consequently should the ventilator become broken a new one may be substituted, thereby 25 by saving the cost of the entire bowl and ventilator.

A further object of the invention is to so construct and arrange the ventilator that the seat may be pivotally connected thereto, 30 thereby eliminating the likelihood of breaking of the bowl when abnormal strain is applied to the seat, as now frequently occurs when the seat is pivotally connected with the bowl.

35 With these and other objects in view, as will appear as the description proceeds, the invention consists in the novel features of construction, combinations of elements and arrangements of parts, and hereinafter to be 40 fully described and pointed out in the appended claim.

In the accompanying drawing:

Figure 1 is a fragmentary side elevation of the device, partly in section and showing 45 the ventilating member in place thereon.

Figure 2 is a sectional view on line 2-2 of Figure 1, and

Figure 3 is a fragmentary plan view of the device.

50 Referring to the drawing 1 designates the bowl, which is formed from vitreous material, said bowl being of the conventional "trap type," and has connected therewith the usual flush water conducting pipe 2, the

water therefrom being discharged into the 55 bowl in the customary manner.

That portion of the bowl immediately above the outlet passage 3 tapers rearwardly to provide a platform 4 which is formed with integral side flanges 5, said flanges 60 having formed therein bolt openings 5, the purpose of which will appear later.

The ventilating member 7 is in the nature of a pipe and is formed from suitable metal and enameled so that when in place upon the 65 bowl it will have the appearance of an integral part thereof. This ventilating member comprises a flared mouth 8 which communicates with the horizontal duct 9, said duct being in communication with a vent or 70 the like and through which the fumes from the bowl are carried by the natural draft through the ventilating member.

The sides of the ventilating member are flared outwardly to produce flanges 10 which 75 are adapted to rest upon the flanges 5 when the ventilator is engaged upon the platform 4, and as more clearly shown in Figure 2 of the drawing. In order to detachably connect the ventilating member to the bowl 80 screw bolts 11 are passed through the flanges 5 and are engaged in the threaded sockets 12 formed in the flanges 10. In this manner it is obvious that the ventilating member may be attached or removed from the bowl 85 upon simply manipulating the bolts, and when in place the forward edge of the flared mouth 8 will overhang the rear end of the bowl, the remaining portion of the mouth being closed by the platform 4. 90

A shaft 13 is supported transversely within the ventilating member and has pivotally connected to its extended ends the arms 14 of the hinge member 15 and to which the seat 16 is attached. Also pivotally connected to the shaft 13 is a controlling stem 17, said stem being disposed longitudinally within the ventilating member and has its rear end connected with a conventional automatic flushing valve (not shown), the 100 movement of the stem being controlled by the arm 18. This arm is shifted to operate the valve when the seat is manipulated, the swinging movement of the arm 18 being regulated through the medium of a screw 19 105 adjustably mounted on the hinge member 15. Thus it will be seen that the valve controlling mechanism is entirely concealed from

view and can not be tampered with by unauthorized persons.

From the foregoing it will be seen that the bowl and ventilating member may be conveniently shipped in a separate state, and readily assembled for use, and since the ventilating member is formed from metal a strong connection is provided for the seat and valve actuating mechanism.

10. What is claimed is:

A water closet bowl of vitreous material and including a platform, a ventilating

member formed from metal, the bowl and member being provided, respectively, with flanges, said members having a flared mouth 15 partially closed by the platform and communicating with the interior of the bowl, and an integral duct in communication with the mouth, and means for detachably connecting the flanges as and for the purpose set 20 forth.

In testimony whereof I affix my signature.

DAVID A. EBINGER.
